UNITED STATES PATENT OFFICE

GORHAM G. CARLSON, OF MINNEAPOLIS, MINNESOTA

WINDOW VENTILATOR

Application filed April 27, 1931. Serial No. 533,078.

My invention has for its object to provide an extremely simple and highly efficient ventilator intended for general use but especially well adapted to be embodied in the lower rail of a window sash.

To the above end, generally stated, the invention consists of the novel devices and combinations of devices hereinafter described and defined in the claims.

10 In the accompanying drawing, which illustrates the invention, like characters indicate like parts throughout the several views.

Referring to the drawing:

Fig. 1 is a fragmentary outside elevation 15 of the lower portion of a window sash having the invention embodied in the lower rail thereof;

Fig. 2 is a view corresponding to Fig. 1 but showing in perspective the inside of the sash 20 and ventilator, the closure plate being open; and

Fig. 3 is a transverse vertical section 25 taken through the sash and ventilator with the closure plate closed and shown in a different position by means of broken lines.

The numeral 4 indicates the lower rail of a window sash 5.

Formed in the intermediate portion of the rail 4 is an oblong ventilating aperture 6. A 30 frame 7 having a screen panel 8 is applied to the outer face of the rail 4, secured thereto by screws and with said screen closing the aperture 6. The frame 7 has the same contour as the aperture 6 and is provided with 35 a vertical cross-tie member 9 in the form of an ornamental figure.

The numeral 10 indicates a closure plate for the ventilating aperture 6 and is secured by a pair of hinges 11, at its lower longitudinal edge, to the rail 4 at the inner face thereof and below said aperture for inward and downward swinging movement. This closure plate 10 is formed from a single sheet of metal, the marginal edge portion of which 40 extends obliquely toward the rail 4, as indicated at 12. When the closure plate 10 is closed its edge has continuous contact with the rail 4 around the aperture 6 and thereby forms a weather-tight joint between the rail and 45 closure plate. The oblique marginal edge 50

portion 12 of the closure plate 10, due to its formation, reinforces said plate and gives the same the necessary rigidity to keep its form. Preferably, as shown, the members of the hinges 11 on the closure plate 10 are formed therewith and the other members of said hinges are directly secured by screws to the rail 4.

A knob 13 by which the closure plate 10 may be opened or closed is secured to said plate at the top and outer face thereof.

To yieldingly hold the closure plate 10 closed or in variable partially open positions there is provided a frictional separable fastener comprising a spring clip 14 and a cooperating blade 15. The clip 14 is U-shaped and secured at its transverse portion to the cross-tie member 9 and extends into the aperture 6 with its flat prongs set vertically edge-wise. The blade 15 is secured to the closure plate 10 on the inner face thereof and arranged to enter between the prongs of the clip 14, spread the same apart and be frictionally held thereby. It will be noted that the outer end portions of the prongs of the clip 14 are in flaring relation so that the blade 15 will freely enter therebetween. When the closure plate 10 is fully open the members of the fastener are separated and said closure plate will be held in an extreme open position by gravity.

A drip flange 16 on the inner face of the closure plate 10 at the bottom thereof extends into the aperture 6 when said closure plate is closed and in case moisture or rain enters or accumulates on the closure plate 10 the same will be directed by said flange into the aperture 6 so as to drain through the screen 8 and outside of the sash instead of between the closure plate 10 and sash.

By directly securing the closure plate 10 to the window sash for direct contact therewith when closed makes an extremely simple, inexpensive and at the same time highly efficient method for closing a ventilating aperture. The separable fastener is automatic in its action to hold the closure plate 10 closed or in variable partially open positions.

What I claim is:

1. In a device of the class described, a clo-

sure plate for a ventilating aperture in a window sash and having hinges directly applicable to the sash for hingedly connecting the closure plate thereto for direct endless engagement with the sash surrounding its aperture to close the same, and a drip flange on the inner face of the closure plate.

2. In a device of the class described, a hinged closure plate for a ventilating aperture in a window sash and applicable to one

side of the sash, a frame having a screen panel applicable to the other side of the sash, said frame having a transverse bar, and a two-part separable fastener which extends transversely through said aperture with one of its parts secured to the closure plate and its other part secured to the transverse bar.

In testimony whereof I affix my signature.

GORHAM G. CARLSON.
